6 Claims. (Cl. 250—27)

1

This invention relates to a device, such as a telegraph transmitter, for controlling an electrical circuit at successive short time intervals, in accordance with respective signal elements pertaining to the different time intervals.

The general object of the invention is to provide a device of the kind described which is capable of reliable high speed performance.

Another object is to provide a keyboard operated telegraph transmitter permitting a partial overlap in operation of two successive keys.

Another object is to provide a device of the kind described providing stable operation over a wide range of supply line voltages.

The invention is in the nature of an improvement upon the transmitter shown in Patent No. 2,210,577, being distinguished from said transmitter by the fact that the signal elements are stored in trigger tubes, rather than in relays.

It is a particular object of the invention to provide a start-stop transmitter of the type shown in Patent No. 2,210,577, which has a smaller size and weight than the earlier transmitter.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a complete circuit diagram of a transmitter embodying the invention.

Fig. 2 is a diagram of the voltage waves of the sequence tubes.

Fig. 3 is a diagram of a typical tone signal transmitted.

Fig. 4 is a diagram of the code signal corresponding to the tone signal shown in Fig. 3.

For the purpose of illustration, the invention is shown embodied in an electronic start stop transmitter of the type shown in Patent No. 2,210,577. Voltage for operating the transmitter is taken from an A. C. line through a plug 7 and rectified by a selenium rectifier 8. The D. C. voltage appears across a condenser 9 at the polarity indicated, and across a voltage divider consisting of resistances 1, 2, 3, 4, 5, and a potentiometer 6. A transformer 10 supplies alternating current to the tube filaments, partially represented at 11, and to a selenium rectifier 12, which sets up a bias voltage across a condenser 13.

The transmitter includes a sweep circuit comprising sequence vacuum tubes V0—V8 and transformers T0—T7. The cathode of the tube V0 is connected by a wire 20 to a point 18 on the voltage divider 1—6, while the cathodes of tubes

2

V1—V8 are connected through a common wire 21 to a point 19 on said voltage divider. The plate of the vacuum tube V0 is connected through the primary winding of transformer T0 and a wire 22 to the positive end of voltage divider 1—6, while the plates of tubes V1—V7 are connected through the primary windings of transformers T1—T7 and a wire 23 to a point 17 on said voltage divider. The plate of tube V8 is connected through a plate resistor 24 and wires 25 and 22 to the positive end of the voltage divider 1—6. The grid of the tube V0 is connected to the cathode of the same tube through a resistance 26. It is also connected through a resistance 28, and wire 22 to the positive end of the voltage divider 1—6. The grids of the tubes V1—V8 are connected through the secondary windings of the respective transformers T0—T7 and a wire 30 to the arm of potentiometer 6.

20 Due to the connections described, the sequence tubes V1—V8 are normally biased off, while the tube V0 is normally conductive, because current is flowing through the resistance 26 in a direction to maintain its grid slightly positive. The sweep 25 circuit comprising the tubes V0—V8 and transformers T0—T7 is designed for sequential operation of the tubes, according to the principle described in the copending application of C. J. Fitch, Serial No. 465,604, filed November 14, 1942 now Patent No. 2,421,606. The sweep is initiated by biasing off the tube V0, in a manner to be described later, thus causing the field in transformer T0 to collapse, inducing a voltage wave in the secondary winding of the transformer and 35 driving the grid of tube V1 positive with respect to its cathode. Current now passes through the primary winding of transformer T1 and tube V1. Also, grid current flows in tube V1, retarding the collapse of the field in transformer T0. When 40 the potential on the grid of tube V1 drops to cathode potential, grid current stops and the field in transformer T0 collapses quickly. The grid potential of tube V1 drops suddenly, cutting off the flow of current through the tube V1 and the primary winding of transformer T1. A voltage wave is induced in the secondary winding of transformer T1 which drives the grid of tube V2 positive with respect to its cathode. The sweep passes down through the sequence tubes in the 45 same manner, each tube remaining conductive for a definite interval, for example, 10 milliseconds (see Fig. 2). The intervals can be adjusted by shifting the arm of potentiometer 6 and thereby changing the normal bias on the grids of the 50 sequence tubes.

There are six gas trigger tubes G1—G6, one for

each code element of the signal. The cathodes of these trigger tubes are connected through a wire 32 to the negative end of the voltage divider 1-6. The plates of the tubes G1-G6 are connected through plate resistors 36 and a wire 37 to the cathode of a vacuum tube V17. The plate of this tube is connected by wires 25 and 22 to the positive end of voltage divider 1-6. The grid of the tube V17 is connected through resistances 38 and 39 (the former shunted by a condenser 41) to the plate of the tube V8. The cathode of tube V17 is connected through a resistance 40 to the negative end of voltage divider 1-6.

The control grids of tubes G1-G6 are connected through grid resistors 42 and wire 41 to an intermediate point 45' of a voltage divider 45 extending from wire 32 to a wire 44 leading to the negative side of condenser 13. The shield grids of the tubes G1-G6 are connected through grid resistors 43 and wire 44 to the negative side of condenser 13. The upper part of voltage divider 45 is shunted by a condenser 46. The screen grids of tubes G1-G6 can be connected through respective normally open contacts C1-C6 and a wire 47 to the cathodes of said tubes. The contacts C1-C6 may be the permutation contacts of a keyboard transmitter, such as shown in Patent No. 2,355,297, or they may be the contacts of a tape reading unit such as shown in Patent No. 2,320,788. The dotted line 48 represents the plug connection of the keyboard transmitter or tape reader to the transmitter circuit.

There are six coupling tubes V11-V16, one for each trigger tube G1-G6. The cathodes of the tubes V11-V16 are connected, respectively, by wires 49 to the plates of the tubes G1-G6. The plates of the tubes V11-V16 are connected to a common signal wire 50. The grids of the tubes V11-V16 are connected through grid resistors 51, grid lead resistors 52, and wire 32, to the negative end of voltage divider 1-6. They are also coupled, respectively, by condensers 53, to the secondary windings of transformers T1-T6. When a sweep is initiated, the grids of the tubes V11-V16 receive in succession, through the condensers 53, positive voltage waves, which condition them for conduction during successive time intervals corresponding to V2-V7 in Fig. 2.

It will be seen, from the connections described, that the vacuum tube V17 is normally conductive, its grid being connected to its plate, and that current flows in resistance 40. Due to the voltage drop in resistance 40, the vacuum tubes V11-V16 are normally biased off, and continue to be so even when the related trigger tubes are conductive. Also, the control grids and shield grids of trigger tubes G1-G6 are normally biased negative and this bias is sufficient so that either grid of each tube will prevent the tube from being ignited. The potential on the control grids can be raised to unlock the tubes G1-G6, by causing current to flow through resistance 45, in a manner to be described presently, in such a way as to lift the potential of the intermediate point 45'.

The screen grids can be brought selectively to cathode potential by closure of the related contacts C1-C6. When the unlocking of a tube by lifting of the potential on its control grid coincides with closure of the related contact C1-C6 the tube will fire. This has the effect of providing a conductive path from the cathodes of the respective coupling tubes V11-V16 to the negative end of voltage divider 1-6. When the potentials on the grids of tubes V11-V16 are

lifted in succession, by operation of the sweep circuit, any tube V11-V16 connected to a trigger tube G1-G6 which is in a conductive state will establish a conductive path from signal wire 50 to the negative end of voltage divider 1-6 and will thereby control a signal output device in a manner to be described presently.

The signal output device comprises a vacuum tube V20, which is an oscillator continuously in operation. Its plate is connected through wire 22 to the positive end of voltage divider 1-6. Its cathode and grid are connected to a tuned circuit comprising a condenser 55 and the primary winding of a variable transformer 56. A point 57 on the tuned circuit is connected by wire 32 to the negative end of the voltage divider 1-6. A grid resistor 58 tends to maintain the frequency of oscillation stable while a cathode resistor 54 provides a bias. The transformer 56 couples the oscillator circuit to the grids of a pair of vacuum tubes V21 and V22 connected in a push pull arrangement. The cathodes of these tubes are connected by wire 23 to the point 17 on the voltage divider 1-6, and are connected to a center tap of the secondary winding of transformer 56 by a connection including a resistance 59. The left end of resistance 59 is connected by a wire 60, and resistance 61 to the signal wire 50. The plates of the tubes V21 and V22 are connected to the end of the primary winding of a transformer 62 connected at a center tap through wire 22 to the positive end of voltage divider 1-6. The transformer 62 couples the amplifier V21-V22 to a pair of amplifier tubes V23 and V24, the grid of V23 being connected through a grid resistor 63 to one end of the secondary winding of transformer 62, while the grid of tube V24 is connected through a grid resistor 64 to a volume control potentiometer 65 shunting the secondary winding of transformer 62. The cathodes of tubes V23 and V24 are connected through cathode resistors 66 to one end of the secondary winding of transformer 62 and, by way of wire 32, to the negative end of the voltage divider 1-6. The plates of tubes V23 and V24 are connected through tuned circuits each comprising a condenser 67 and the primary winding of a transformer TM or TS, and through the wire 22, to the positive end of the voltage divider 1-6. The output of transformer TM goes to a monitoring device (not shown), while the output of transformer TS is sent through any suitable communication channel.

Operation

Normally, that is, during the standby period, while the vacuum tube V20 is oscillating, the oscillations are shut off from the transformers TM and TS by a voltage drop in the resistance 59, which biases off the amplifier tubes V21 and V22. This voltage drop is caused by current flowing from the point 17 of voltage divider 1-6 through wire 23, resistance 59, wire 60, a resistance 70, the plate to cathode path through a standby trigger tube G9 (which is normally conductive for a reason to be described presently), wire 71, branching through resistance 45 and wires 32 and 44, to the negative end of voltage divider 1-6 and the negative side of condenser 13, respectively.

The potential of the point 45' is elevated above that of wire 32 and the trigger tubes are thereby unlocked.

In accordance with the signaling system chosen for illustration, each complete signal consists of a start signal, six code signal elements, and a

stop signal (see Fig. 4). The start signal and spacing signal elements are represented by oscillations, while the stop signal and marking signal elements are represented by no oscillations (see Fig. 3).

Associated with the contacts C1—C6 is a start contact CS, which is closed when any one of the contacts C1—C6 is closed (see contact 96 of Patent No. 2,355,297). One side of contact CS is connected by wire 47 to the negative end of voltage divider 1—6, while the other side is connected to the shield grid of a gaseous start tube G8. This grid is normally biased to cut-off the tube by connection through a resistor 90 and wire 44 to the negative bias terminal of rectifier 12. The cathode and control grid of the tube G8 are connected by wire 32 to the negative end of the voltage divider 1—6. The plate of tube G8 is connected to the cathode of a vacuum tube V10, whose plate is connected by a wire 75, resistance 26, and wire 20, to the point 18 of voltage divider 1—6. The grid of the tube V10 is connected through a grid resistor 76 to wire 20 and thus the tube V10 is normally conductive.

Assume that the standby tube G9 is in a conductive state, so that signal output is shut off and the potential on the control grids of tubes G1—G6 is high. Now if, by operation of the typewriter keyboard in Patent No. 2,355,297, or the tape reader in Patent No. 2,320,788, the contacts C1, C4, C5, and CS are closed, tubes G1, G4, and G5 will be ignited immediately.

When contact CS is closed, the shield grid of tube G8 is brought up to cathode potential and the tube is fired, and current flows through a circuit extending from the point 18 of the voltage divider 1—6 through wire 20, resistance 26, wire 75, tubes V10 and G8, and wire 32, to the negative end of voltage divider 1—6. The voltage drop through resistance 26 biases off the normally conductive tube V10 and starts the sweep sequence. It also transmits a negative voltage wave through a condenser 78 to the plate of tube G9 and extinguishes this tube. This cuts off the flow of current through resistance 45, causing a negative biasing potential to be applied to the control grids of the tubes G1—G6, which prevents any of these tubes not initially ignited from being ignited, so long as the gas tube G9 remains non-conductive. Also, when the tube G9 is extinguished, current flow through the resistance 56 ceases and oscillations are passed to the TM and TS transformers. This constitutes the start element of the signal (see Figs. 3 and 4).

During the start signal element the sweep tube V1 is conductive. When its conductivity is terminated by the collapse of the field in transformer T1, a positive pulse is transmitted through transformer T1 to the grid of tube V2 and, through condenser 53, to the grid of tube V11, rendering both of these tubes conductive. This starts the readout of the set of trigger tubes G1—G6, in which the signal 1, 4, 5 is stored. Since, in accordance with the example, the tube G1 is in a conductive state when the coupling tube V11 becomes conductive, a circuit is completed from the point 17 of the voltage divider 1—6 through wire 23, resistance 59, wire 60, resistance 61, wire 59, the plate-cathode path of tube V11, wire 49, the plate-cathode path of tube G1, wire 32, to the negative end of voltage divider 1—6. The voltage drop across the resistance 59 biases off the amplifier tubes V21 and V22, cutting off the oscillations from the transformers TM and TS. This constitutes a marking element, in conformance with the

first signal element of the signal selected for illustration (see Figs. 3 and 4).

When the field in transformer T1 collapses and the tube V2 becomes non-conductive, a positive pulse is transmitted to the grids of tubes V3 and V12, rendering these tubes conductive. Since the tube G2 is in a non-conductive state, current does not flow through resistance 59 and oscillations are transmitted to the transformers TM and TS during the second element of the signal. During the third element of the signal, the corresponding tube G3 interrupts the circuit through the resistance 59 and signal wire 50 and oscillations continue to be transmitted to the transformers TM and TS. Tubes G4 and G5 being ignited, during the fourth and fifth signal elements current will pass through resistance 59 and oscillations will not reach the transformers TM and TS. During the sixth signal element, the tube G6 being non-conductive, oscillations will be transmitted to the transformers TM and TS.

When vacuum tube V1 is cut off by the collapse of the field in transformer T6, a positive pulse is transmitted to the grid of normally non-conductive vacuum tube V8, rendering this tube conductive. A negative pulse is transmitted from the plate of tube V8 through condenser 41 and grid resistor 39 to the grid of normally conductive tube V17, rendering this tube non-conductive. This cuts off the plates of the trigger tubes G1—G6 from the voltage supply and extinguishes any tubes which were in conductive state. At the same time, the negative voltage wave from the plate of tube V8 is transmitted through a wire 80 and condenser 81 and part of grid resistor 76 to the grid of tube V10, biasing off this tube and extinguishing gas tube G8. When tube V10 is biased off, the potential of its plate rises and a positive voltage wave is transmitted through a condenser 82 to the control grid of gas tube G9, rendering this tube conductive. This restores the standby condition, but the next signal cannot be started immediately, because the tubes V10 and V17 remain non-conductive as long as the tube V8 continues to conduct. After a brief time, the field in the transformer T7 collapses and the tube V8 is cut off. This restores the conductivity of tube V17, applying positive potential to the plates of the tubes G1—G6. Also, it restores the tube V10 to a condition in which it can conduct.

If after this a new combination, say 245, is set up on the contacts C1—C6, the trigger tubes G2, G4 and G5 will be ignited. Also, the contacts CS will be closed and the start tube G8 will be ignited. The transformers TM and TS will accordingly be controlled in a manner similar to that previously described, to transmit the signal 245.

The circuit parameters may be determined so that each signal element is equal to 10 milliseconds, for example. Since there are eight elements in each signal, namely, start, stop and six code elements, the total time of one complete cycle of operation would then be 80 milliseconds. This is equivalent to 12½ cycles or characters per second or 125 words per minute. If the keyboard permutation selector controlling the contacts C1—C6 and CS is so constructed and conditioned as to keep the contacts closed for about 45 milliseconds, it is possible for the second key to be depressed 40 milliseconds after the first key, because the contacts closed by the second key will remain closed 5 milliseconds beyond the

termination of the first signal. For example, if a key is depressed which closes the contacts 2, 4 and 5, 40 milliseconds after the previous key was operated, this has no immediate effect upon the trigger tubes G1—G6 because at this time the control grids of these tubes have a negative bias, which makes the tubes indifferent to potentials applied to the shield grids. During the last 10 milliseconds of the first signal, the tubes V17 and V10 are biased off, and during this time the standby tube G9 is conductive, the signal generator is biased off, and the both grids of the tubes G2, G4 and G5 are so conditioned that the tubes would be ignited if their plates were positive.

Likewise, although the shield grid of the tube G8 is at cathode potential because the contact CS is closed, this tube is non-conductive because the tube V10 is cut off. When the tube V8 is biased off at the end of the 80 milliseconds which marks the termination of the first signal, the vacuum tube V17 is restored to conductivity and the tubes G2, G4 and G5 are ignited. Also, the vacuum tube V10 becomes conductive and the tube G8 is ignited. This starts the second signal. The contacts C2, C4 and C5 are opened 5 milliseconds after the start of the second signal.

The effect of this overlap is that for two successive signals, keys can be operated 40 milliseconds apart or at the rate of 250 words per minute. (The third key, of course, cannot be operated until 80 milliseconds after the second key.) This allows a high speed typist to average over 100 words per minute, giving in effect a free keyboard.

During partial overlap, as described above, tube V17 is unlocked at the same instant that G9 is extinguished. Since the tubes G1—G6 will not ignite until after V17 unlocks, and since they cannot ignite after G9 is extinguished, it is necessary to provide some delay in the decay of the bias voltage on the control grids of the tubes G1—G6. This delay is provided by the condenser 46.

When power is first applied to the circuit, the standby tube G9 is non-conductive, and oscillations are continuously transmitted to the transformers TM and TS. By closing the contact CS the standby condition is established, the tube G9 being ignited and the oscillations being cut off from the transformers TM and TS.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a transmitter, a set of gaseous trigger tubes for storing respective signal elements, means including a set of signal element contacts pertaining respectively to said trigger tubes for selectively igniting said trigger tubes, signal output means, readout means including a plurality of sequentially operable devices for subjecting said signal output means to the control of each of said trigger tubes in succession, means including a normally non-conductive trigger tube for starting said readout means, means for igniting said starting trigger tube including a start contact adapted

to be closed whenever any one of said signal element contacts is closed, means responsive to the last one of said sequentially operable devices for extinguishing said starting trigger tube, a stand-

- 5 by device for controlling said signal output means during the standby period, means coupling said standby device to said starting trigger tube so that said standby device is turned off and on as said starting trigger tube is ignited and extinguished, respectively, and means controlled by said standby device for locking said signal element trigger tubes during the time said standby device is off and releasing the same for selective ignition while said standby device is on.
- 15 2. In a transmitter for operation by a keyboard having a plurality of combinationally operated signal element contacts and a start contact which is closed whenever any one or more of the signal element contacts is closed; a set of gaseous trigger tubes, one for each of said signal element contacts, for storing respective signal elements, each of said trigger tubes having an anode, a cathode, and two grids; a voltage source; means connecting the anodes, the cathodes, and the grids 20 of said trigger tubes to said voltage source so that each grid is normally biased to a potential sufficiently low to prevent ignition of the tube, each of said signal element contacts being connected to one grid of the related trigger tube and to said voltage source in such a way that when a contact is closed the bias on the related grid is reduced sufficiently to release the tube to the control of its other grid; a gaseous standby tube connected to said voltage source and to all of the second grids 25 of said trigger tubes in common, in such a way as to remove the bias potential from said second grids when said standby tube is ignited; signal output means; readout means including a plurality of sequentially operable devices for subjecting said signal output means to the control of each of said trigger tubes in succession; start means controlled by said start contact for starting the operation of said readout means; means controlled by said start means for extinguishing said 30 40 45 50 55 60 65 70 75 80 85 90 95 100 standby tube and restoring the cut-off bias to said second grids of the trigger tubes; means controlled by the last of said sequentially operable devices for cutting off said voltage source from the anodes of said trigger tubes, to extinguish any ignited trigger tubes; and means also controlled by the last of said sequentially operable devices for igniting said standby tube, to remove the cut-off bias from the second grids of said trigger tubes.
3. In a transmitter, a voltage source, a signal output circuit including a control element, a set of storage trigger tubes for storing respective signal elements, a start trigger tube, each of said trigger tubes comprising an anode, a cathode and a grid, means for connecting the anodes of said storage trigger tubes to said voltage source comprising a single grid controlled vacuum tube for all anodes and a plurality of current limiting resistors for the individual anodes, means for connecting the anode of said start tube to said voltage source including a grid controlled vacuum tube, means for connecting the cathodes and grids of said trigger tubes to said voltage source so that said grids are normally biased to a cut-off potential, storage control means for selectively controlling the potential on the grids of said trigger tubes to ignite said tubes selectively in combinations, start control means operated in conjunction with said storage control means for controlling the potential on the grid of said start tube

to cause said tube to ignite, means for additionally connecting the anodes of said storage trigger tubes to said voltage source through the control element of said signal output circuit, said last connecting means comprising parallel circuit means for the respective anodes, each including a sequence control device, sweep circuit means to condition said sequence control devices sequentially, to provide conductive paths from the voltage source through the control element of said signal output circuit to the anode of each of said trigger tubes in succession, means controlled by said start tube for initiating an operation of said sweep circuit means, and means operated by said sweep circuit means at the end of a sweep for applying a negative voltage impulse to the grids of said vacuum tubes, to extinguish any ignited storage tubes and the start tube.

4. A transmitter as described in claim 3, characterized by the fact that said storage trigger tubes have second grids connected to said voltage source so as to have a normal bias preventing the ignition of said storage tubes, a gaseous standby tube, means connecting said standby tube to said second grids and to the voltage source and adapted to reduce the bias on said second grids, when said standby tube is conductive, to release said storage tubes for control by their first mentioned grids, and means coupling said standby tube to the vacuum tube connected to said start trigger tube, so that said standby tube is ignited when said vacuum tube is made non-conductive by a negative voltage impulse at the end of a sweep and is extinguished when said vacuum tube becomes conductive again.

5. In a transmitter for operation by a keyboard having a plurality of combinationally operated signal element contacts and a start contact which are held closed for a definite period of time when operated, said start contact being closed whenever any one or more of said signal element contacts are closed; a set of gaseous trigger tubes, one for each of said signal element contacts, for storing respective signal elements, each of said trigger tubes having an anode, a cathode, and control electrode means, a voltage source, means connecting the anodes, the cathodes, and the control electrode means of said trigger tubes to said voltage source, locking means whereby the voltage applied to said control electrode means can be conditioned to prevent the ignition of said trigger tubes, voltage controlled means for con-

ditioning said locking means to unlock or to lock said trigger tubes, voltage controlled means for interrupting the anode connection of said trigger tubes to said voltage source, means including said signal element contacts for selectively igniting said trigger tubes when said locking means is conditioned to permit them to be ignited, signal output means, readout means including a plurality of sequentially operable devices for subjecting said signal output means to the control of each of said trigger tubes in succession, means controlled by said start contact for starting the operation of said readout means, means controlled by the last of said sequentially operable devices for transmitting a voltage impulse to each of said voltage controlled means, whereby any ignited trigger tubes are extinguished and the tubes are released by said locking means for the duration of said voltage impulse, means to delay the return of said locking means to locking condition until a short time after the anode connection to said trigger tubes is restored to conductive condition at the end of said voltage impulse, and means whereby said locking means is additionally controlled by said starting means, to maintain said trigger tubes in an unlocked condition, after the transmission of one signal, until said start contacts are closed to initiate another signal.

6. A transmitter as described in claim 5, characterized by the fact that said last mentioned control means for said locking means comprises a trigger tube and a vacuum tube in series connection, said last mentioned trigger tube being controlled by said start contact and said vacuum tube being controlled by the impulse from said voltage impulse transmitting means.
